MUFFLED VIBRATOR

James E. Becker, Rocky River, Ohio

Application February 8, 1955, Serial No. 486,820

2 Claims. (Cl. 121—17)

The invention relates to industrial vibrators such as are used, for example, to facilitate discharge of granulated or nondescript comminuted material from sloping walled containers, such as discharge of sand or slag from railroad hopper cars, bins, and chutes. Other familiar uses are, for example, vibration tables, foundry shake-outs, pneumatic hammers or the like.

As is familiar to those skilled in related arts of this type, a vibrator usually operates on a principle involving rapid reciprocation, or perhaps off-center rotation, of a movable element within a housing, said housing being bolted or otherwise firmly attached to the article which must be vibrated, such as the cope of a mold or the body of the bin or hopper car. Compressed air is the usual motive power for the vibrator, and the exhaust air normally escapes to atmosphere, the resulting air disturbance causing loud, and harsh noises, the pitch of course depending on the frequency of successive exhaust discharges. In an enclosed space such as a factory or workshop, or when attached to a steel walled hopper or other container, the resultant noise can be most irritating to anyone in the vicinity. The ordinary pedestrian has been subjected to the disturbing effect created by the use of pneumatic hammers by pavement workers.

An object of the present invention is to provide a pneumatic power tool of the vibrator type wherein the exhaust discharge noise is reduced almost to an imperceptible level, certainly to a non-irritating level, without reducing the efficiency of the vibrator.

Another object of the invention is to provide a vibrator of the type defined in the last preceding paragraph which can be manufactured at a cost not substantially exceeding the cost of a conventional non-muffled vibrator.

Other objects and advantages will be apparent from a study of the following description of several embodiments of the invention, in conjunction with the accompanying drawings, in which:

Fig. 1 is a sectional view taken axially on a vibrator embodying my invention.

Fig. 2 is a view partly in plan and partly in section, showing a slightly modified form of my invention.

Fig. 3 is a view similar to Fig. 2 but showing yet another embodiment of the invention.

Fig. 4 is an enlarged view showing a structural detail of part of the apparatus shown in Fig. 3.

Referring first to Fig. 1, there is shown a housing 10 of tubular character and of sturdy construction having a bored aperture 11 therethrough, the aperture being closed at both ends by end plates 12 and 13 which are held in tight, leak-proof contact with the body by tie bolts 14. The tie bolts can pass outside the body, as indicated in the embodiments of Figs. 2 and 3, passing between lugs in the end plates which clear the body portion 10. Obviously the end plates could be held in place by studs threaded into tapped apertures in the body, although the method I show avoids the necessity of drilling and tapping the body ends.

2

A reciprocable member, or piston 15 has a slidable fit within bore 11 and it has two annular peripheral grooves 16 and 17, groove 16 having fluid flow communication with the piston end 15a through passage 16a, and groove 17 being in communication with the piston end 15b through passage 17a thereby providing access to end head chambers 18 and 19.

A bored exhaust passage 20 extends longitudinally through the body wall, and it has two ports 21 and 22 communicating with respective opposed end chambers 18 and 19. End plate 13 has exhaust ports 23 establishing communication between exhaust passage 20 and atmosphere. Spaced from exhaust passage 20 the body wall has an air inlet port 24 located centrally to permit periodic registry with either groove 16 or groove 17 on the piston 15. To facilitate proper operation, as described immediately hereinafter, the inner body wall has an annular groove 25 in registry with port 24. Exhaust passage 20 is packed with permeable material such as bronze wool 27, or any sound deadening material.

In operation the device functions as follows. In the position shown in Fig. 1, grooves 16 and 25 are in registry. If compressed air is admitted through port 24, it will pass through passage 16a to end chamber 18, whereupon piston 15 is thrown towards the left end. This movement quickly interrupts communication between port 24 and passage 16a but the piston continues its movement (chamber 19 being still vented through outlets 22, 28, and 23 in succession) until piston end 15a clears outlet 21 at 30 which time chamber 18 is vented to exhaust through 21, 20, and 23, and passage 22 is closed by piston end 15b. At this stage compression of residual air in chamber begins to impede the movement of piston 15, and about the same time groove 17 comes to registry with groove 25 and port 24 thereby admitting compressed air through passage 17a to chamber 19, reversing the piston motion and completing a cycle. All this of course takes place with great rapidity. In this design the piston never comes to actual contact with either plate 12 or 13.

It will be observed that the exhaust air, from chambers 18 and 19 alternately, passes through respective passages 21 and 22, and then through the permeable material 27 before passing outwardly through vents 23 to atmosphere. I have found that the provision of the muffling passage 20 very materially quiets the operation of the vibrator so that it becomes actually unnoticeable except for a slight hissing noise, and there is no sensation of "motor boating," or no siren-like noise, these latter two phenomena being exemplifications of low or high frequency exhaust discharges. The invention of course is not limited to vibrators of the type just mentioned, but can also be utilized in connection with rotary type vibrators in which the exhaust is practically continuous.

In the embodiment of Fig. 1, it will be noted that the ultimate discharge is all through the right end so that the alternate discharges from chambers 18 and 19 pass through respectively varying amounts of muffling material. In the embodiment illustrated in Fig. 2, the ports 28 have been drilled centrally of the length of the exhaust passage 20a, so that air escaping from either of the end chambers of the cylinder travels through approximately the same amount of muffling material.

Figs. 3 and 4 show another embodiment wherein the exhaust chamber 20b has a conventional type of muffler inserted therein. Any type of noise-muffling device will be satisfactory as long as it is adaptable to the somewhat limited space requirements of the exhaust passage 20b. Merely as an illustration, I show several concentric tubes 29 and 30, spaced from each other and from the exhaust passage wall. The tubes have a plurality of perforations 31 therethrough, and there are annular spacers 32 which

serve to baffle air flow and maintain the spacing of the tubes. This type of muffler can be manufactured separately and inserted endwise into chamber 20b. Air emerging from port 33, for example, must travel through a circuitous course before exhausting to atmosphere through vents 34, while undergoing successive expansions.

What I claim is:

1. Vibrator means of the character described comprising an elongated body having an axial aperture therein, an inlet port to each end of said aperture from the body exterior, a second aperture in the body wall generally parallel to said first aperture, and having an opening to atmosphere, a pair of exhaust ports, one from each of the opposite ends of said first aperture and opening into said second aperture, said second aperture being filled with noise muffling material, and an element in said first aperture

rapidly reciprocable responsive to admission of pressure fluid to said inlet port.

2. Vibrator means as defined in claim 1 wherein the opening to atmosphere from said second aperture is substantially evenly spaced from, and between, said exhaust ports whereby the exhaust from each end of the said first aperture travels approximately an equal distance through said noise muffling material.
